UNITED STATES PATENT OFFICE.

DAVID SANDERSON, OF OTTAWA, ILLINOIS.

AIR-COOLING REFRIGERATOR.

SPECIFICATION forming part of Letters Patent No. 296,071, dated April 1, 1884,

Application filed January 24, 1884. (No model.)

To all whom it may concern:

Be it known that I, DAVID SANDERSON, of Ottawa, La Salle county, Illinois, have invented a new and Improved Air-Cooling Refrigerator, of which the following is a full, clear, and exact description.

The object of my invention is to provide certain new and useful improvements in the ice-beds of refrigerators, whereby the air can be caused to circulate well around the ice in the ice-rack, and thus cool the air in the room in which the refrigerator is placed.

The invention consists of the combinations of parts and their construction, substantially as hereinafter fully set forth, and pointed out in the claims.

Reference is to be had to the accompanying drawings, forming a part of this specification, in which similar letters of reference indicate corresponding parts in all the figures.

Figure 1 is a longitudinal sectional elevation of a refrigerator provided with my improvements. Fig. 2 is a cross sectional elevation of the same on the line $\alpha\alpha$, Fig. 1.

The ice-bed A in the refrigerator B is made hopper-shaped—that is, it is inclined from the sides and ends of the refrigerator to an oblong opening or slot, C, formed in the said ice-bed. A gutter, D, is formed on the ice-bed around the slot or opening, which gutter is provided with an outlet-pipe, E. The ice-rack F, on which the ice is placed, is placed on the ice-bed A in the manner shown, and to the under side of the rack a curved metal plate, G, is fastened, the said plate being curved downward from the longitudinal middle axis of the plate toward both side edges. The water that drips from the ice through the rack F flows down the curved plate G upon the ice-bed A, and down the inclined sides of the same into the gutter D. A slot or narrow oblong opening, R, in the upper sides of the refrigerator, near the top, acts as an outlet or vent for the warm impure air that pervades the upper portion of the cooling-room in which the refrigerator is placed, allowing this air to pass

in upon the ice on the rack, thereby causing the impurities the air contains to be deposited thereon and pass off through the meltage-water by pipe E, while the air, being refreshed and purified, sinks by its own weight downward through the slats and hopper-shaped ice-bed, and is diffused over the cooling-room through slot C on the under side of the ice-bed, thus producing a cold dry atmosphere, free from moisture and impurities, and thereby automatically serving as a ventilator by its own natural action. The space between the ice-rack and the ice-bed permits of a thorough circulation of the air.

The above-described ice-bed can be placed in any refrigerator, large or small. By means of it the air in a room can be cooled and be kept perfectly dry and pure without the use of a ventilator, thus giving the cooling-room in which it is placed a lower temperature.

Having thus described my invention, I claim as new and desire to secure by Letters Patent—

1. In a refrigerator, the ice-rack having the curved plate or deflector affixed at about its central upper portion to the under side of said rack, in combination with the hopper-shaped ice-bed having a central oblong air-passage in its lower convergent portion, substantially as and for the purpose set forth.

2. In a refrigerator, the ice-rack having the curved plate or deflector affixed at about its central upper portion to the under side of said rack, and the hopper-shaped ice-bed having a central oblong air-passage and a drip-gutter around said passage, in combination with the case or inclosure having air-passages in its upper portion, the tube forming the ice-bed air-passage extending through the bottom of said case or inclosure, substantially as and for the purpose set forth.

DAVID SANDERSON.
